(57) **CLAIM**

The ornamental design for an electronic device with battery pack, substantially as shown and described.

DESCRIPTION

FIG. 1 is a perspective view showing my new design; FIG. 2 is a front view thereof; FIG. 3 is a back view thereof; FIG. 4 is a right side view thereof; FIG. 5 is a left side view thereof; FIG. 6 is a top view thereof; FIG. 7 is a bottom view thereof; FIG. 8 is another perspective view thereof; FIG. 9 is an explosive view showing the electronic device and battery pack in an unmated configuration; FIG. 10 is a perspective view showing an alternate embodiment thereof; FIG. 11 is another front view thereof; FIG. 12 is another back view thereof; FIG. 13 is another right side view thereof; FIG. 14 is another left side view thereof; FIG. 15 is another top side view thereof; FIG. 16 is another bottom side view thereof; and, FIG. 17 is another perspective view thereof.

The broken line seen on the lower portion of the article in FIG. 9 defines the bounds of the claimed design and forms no part thereof. The broken line bracket seen in FIG. 9 forms no part of the claim.
